UNITED STATES PATENT OFFICE.

HENRY GARDENIER, OF PATERSON, NEW JERSEY.

CLOSET-VALVE.

1,218,251.

Specification of Letters Patent.

Patented Mar. 6, 1917.

Application filed October 4, 1915. Serial No. 54,020.

To all whom it may concern:

Be it known that I, HENRY GARDENIER, a citizen of the United States, residing at Paterson, in the county of Passaic and State 5 of New Jersey, have invented certain new and useful Improvements in Closet-Valves; and I do declare the following to be a full, clear, and exact description of the invention, such as will enable others skilled in the art 10 to which it appertains to make and use the same.

This invention relates to improvements in flushing apparatus for water closets particularly the valves therefor, which are of 15 such a type that when a suitable operating arm is moved in one direction, water is allowed to enter the flushing tank, and when the arm is moved in the opposite direction, the inlet port is closed and the outlet port 20 opened to permit the water from the tank to be discharged into the bowl.

The object of my invention is to provide a valve of this type from which all of the movable operating parts may be quickly 25 and easily removed at any time.

With this general object in view, my invention resides in the novel features of construction, combination and arrangement of parts which will hereinafter be more fully 30 described and claimed.

In the accompanying drawing:

Figure 1 represents a front elevation of my improved valve;

Fig. 2 is a top plan view thereof;

Fig. 3 is a vertical transverse section taken on the line 3—3 of Fig. 1;

Fig. 4 is a longitudinal section taken on the line 4—4 of Fig. 2;

Figs. 5 and 6 are horizontal sections 40 taken on the lines 5—5 and 6—6 respectively of Fig. 1;

Fig. 7 is a detail horizontal section showing the construction of the valve stem with one of the valves in position; and

Fig. 8 is a detail transverse section taken on the plane of the line 8—8 of Fig. 7.

In the embodiment illustrated, my improved valve comprises a casing 1 which is mounted upon a suitable base 2; said casing 50 1 being open at its ends as shown at 3 which are normally closed by removable caps 4. The casing 1 is here shown as substantially cylindrical in shape with a bore 5 extending throughout its length, said bore verging 55 into an enlarged chamber 6 formed intermediate the ends of the casing. The cham-

ber 6 extends upwardly to provide a housing 7 in which is mounted a suitable valve operating means which will be more particularly described. The upper end of the 60 housing 7 is provided with an internally threaded nipple 8 into which a pipe 9 leading to a flush tank (not shown) is threaded, while an additional nipple 10 is formed preferably on the front of the face of said 65 housing 7 and is adapted to receive a stuffing box 11 thereon.

The casing 1 is also provided with an inlet port 12 and an outlet port 13 which are disposed adjacent the open ends 3 thereof 70 between said ends and the chamber 6 and are surrounded by the internally threaded nipples 14 and 15, a water inlet pipe being threaded into the nipple 14 while an outlet pipe is similarly connected to the nipple 15. 75 The bore 5 of the casing 1 is shown contracted to provide valve seats 16 and 17, one of which is disposed between the chamber 6 and the inlet port 12 and the other between said chamber 6, and the outlet port 13. 80 These reduced portions also serve to separate the chamber 6 from the rest of the casing and form cylindrical guides for a valve stem 18.

The valve stem is slidably mounted within the casing 1 and is formed of a main body portion 19 having threaded sockets 20 in its opposite ends, and valve carrying portions 21 which are here shown as having heads 22 integrally connected with reduced shanks 23, the free ends of which are threaded for engagement with said sockets 20. The valves preferably used for coaction with the seats 16 and 17 are what are well known as "Fuller" balls 24 having central apertures through which the shanks 23 are adapted to extend, the balls being clamped between the heads 22 and the ends of the body portion 19 of the valve stem when the threaded ends are screwed into 100 the sockets 20. As shown in Fig. 7, the ends of the body portion 19 are concave to receive the rounded end of the ball valve 24, while the heads of the portions 21 are undercut for the reception of the conical shaped opposite ends 24' of said valve. From this description it will be seen that these balls are readily removable should they become worn and the valve have a tendency to leak. In removing the same, it 105 is simply necessary to remove the cap members 4 and then screw the shanks 23 from

the main body portion 19 of the stem, the heads 22 being slotted to facilitate such removal.

I preferably provide these caps 4 with 5 the sockets 25 which act as guides for the ends 22 of the valve stem as disclosed in Figs. 4 and 5. The main body portion 19 of the valve stem is further provided 10 with grooves 26 which act as water passageways and are adapted to allow water to pass around the contracted portions of the bore 5 of the casing from the port 12 to the chamber 6, or from the chamber 6 to the port 13. It is evident that when the ball 15 valves 24 coact with their seats, the water cannot pass through the grooves 26 in the stem. It is also obvious by reference to Figs. 3, 4 and 5 of the drawing, that only one of the valves 24 is active at a time and 20 that because of the peculiar disposition of the Fuller balls, the water when entering the valve casing does not come into forcible contact therewith as in the ordinary type of valves; thus the valves are protected and 25 last considerably longer.

A rock shaft 27 extends through the stuffing box 11 and has its inner end reduced and is adapted to coact with a bearing formed in the wall of the housing 7 so as to allow 30 said rock shaft to readily rotate. Depending from the end of the shaft within the housing 7 is a crank 28 whose lower end coacts with a seat 29 formed in the body portion 19 of the valve stem. The free end of 35 the rock shaft 27 has formed thereon or connected thereto in any suitable manner an operating arm 30 which preferably extends equal distances on each side of the shaft. The opposite ends of the arm 30 are aper- 40 tured as shown at 31 and are adapted to receive a suitable operating cord 32, one portion of said arm receiving a removable normally stationary weight 33 which may be moved to any desired position on either por- 45 tion of the operating arm.

By pulling upwardly on the cord attached to the portion of the arm carrying the weight 33, the rock shaft will be rotated and cause the crank 28 to move the valve stem to open 50 the port 12 and which allows water to enter therein, pass through the grooves 26 and into the chamber 6 from which it passes upwardly through the pipe 9 and into the flushing tank. When, however, this operating 55 cord 32 is released, the weight 33 will cause the arm to move in the opposite direction, thus closing the inlet port 12 and opening the outlet port 13 which was closed during the preceding operation. This opening 60 of the outlet port 13 will permit the water contained in the flushing tank to descend through the pipe 9, through the other grooves 26 and out through the port 13 to the closet bowl, thereby flushing the same. 65 The valve will remain in this position until

the operating cord is again pulled to allow water to enter the inlet port 12.

As both end portions of the valve are structurally alike, both of the ports 12 and 13 may readily be used as either inlet 70 or outlet ports. In changing the direction of flow of water from the port 12 to the port 13 as illustrated, it is simply necessary to reverse said ports, permitting the port 13 to become the inlet and 12 the outlet port, and 75 to change the weight 33 and the cord 32 to the opposite portions of the arm 30. This is an important feature of my invention and gives the valve a wide range of adaptability.

From the foregoing description, it will be 80 seen that I have produced a valve which will prevent the freezing of water in the flushing tank or in the pipes leading thereto or therefrom, because the tank is automatically emptied whenever the operating cord is re- 85 leased. It is also evident that by providing the inlet ports in the side of the casing and closing the open ends of said casing with removable caps, the valves on the stem 18 are readily removable when it becomes necessary 90 to repair the same without disconnecting the entire casing of the valve from the connecting pipes.

While I have particularly described the 95 elements best adapted to perform the functions set forth in my invention, it is obvious that various changes may be resorted to within the scope of the appended claim without departing from or sacrificing any of the principles of this invention.

I claim—

In a valve of the class described, an open ended casing having a cylindrical bore throughout its length, the diameter of the bore being reduced at two spaced apart 105 points within said casing to form cylindrical guides, the opposite ends of said casing being externally threaded, a housing formed integrally with said casing and rising therefrom between said reduced portions, a water pipe 110 extending from said housing, a valve stem in said bore and slideable in said guides, the intermediate portions of said stem being grooved to permit water to enter said housing, the opposite ends of said stem being 115 cupped and provided with threaded sockets, ball valves in said cupped ends, a valve seat formed in the outer side of each of said reduced portions for the reception of said ball valves, valve carrying members comprising 120 threaded shanks extending through said valves and engaged with said threaded sockets, and undercut heads whereby the valves are clamped between the same and the ends of said stem, said heads being slotted, 125 internally threaded caps on the threaded ends of said casing, guide sockets formed integrally with said caps to receive said slotted heads, said caps being readily removable to permit the removal of said ball valves 130

and stem without dismounting said valve casing, an inlet port formed in the wall of said casing between one of the valve seats and the end thereof, an outlet port formed 5 in the wall of the casing between the other valve seat and the opposite end thereof, said ports communicating with the bore of said casing and extending at right angles to the axis thereof, whereby water may readily enter said casing without interference with 10 said valves, a rock shaft rotatable in said housing, a crank depending from said shaft within the housing, said valve stem having a seat to receive the end of said crank, an 15 operating arm fixed to the outer end of said rock shaft and extending equal distances on each side thereof, and a normally stationary removable weight carried by one of said arms to normally retain one of said valves in engagement with its seat and hold 20 the other open to permit water to flow into or out of said housing, said weight being movable to the other end of said arm in order to hold the other valve open, and thereby change the direction of flow of the water. 25

In testimony whereof I have hereunto set my hand in presence of two subscribing witnesses.

HENRY GARDENIER.
